(57) **CLAIM**

I claim the ornamental design for a game board, as shown.

DESCRIPTION

FIG. 1—is a front prospective view of a game board showing my new design;

FIG. 2—is a top view thereof;

FIG. 3—is a side elevational view, the opposite side appearing identical;

FIG. 4—is a end elevational view, the opposite end appearing identical; and,

FIG. 5—is a bottom plan view thereof.
